UNITED STATES PATENT OFFICE

2,461,771

ROTARY DUMP

Erskine Ramsay, Birmingham, Ala.

Original application October 30, 1944, Serial No. 560,930. Divided and this application September 8, 1945, Serial No. 615,185

2 Claims. (Cl. 214—52)

1

This application is a division of my previously filed application, Serial No. 560,930, filed October 30, 1944.

This invention relates to a mine haulage system, in which an endless cable is employed to haul mine cars into and out of a mine, which cars engage the cable with a detachable grab, and has for an object the provision of apparatus of the character designated which shall include a rotary dump through which the cable passes and which is adapted to dump the cars while in longitudinal motion.

A further object of my invention is to provide, in a mine haulage system, a rotary dump having means to engage and support the cars while being rotated through an angle of 180° and while moving longitudinally through the dump.

Mine haulage systems have, heretofore, been proposed in which an endless cable was run over parallel tracks in a mine tunnel or slope and in which the cars engaged the cable with detachable grabs mounted on the ends of the cars. All such apparatus with which I am familiar entailed frequent starting and stopping of the drive means for the cable, and for detaching the loaded cars as they came out of the mine for passage through the rotary dump. This necessitated the employment of considerable manual labor for placing the cars in the rotary dump and removing them therefrom, and afterwards for re-engaging them with the cable.

In accordance with my present invention, I employ the endless cable and the parallel tracks in the mine, and include in the driving means for the cable, a relatively large sheave at the head of the tipple beneath and around which the track runs, and provide means associated with the sheave for engaging the mine car grabs and carrying them around the track and the sheave. I also provide a rotary dump through which the endless cable passes, which rotary dump is adapted to dump the cars and right them while they are still in motion longitudinally through the dump. By the means employed, there is no necessity of uncoupling the cars from the cable in order to dump them, and accordingly they are hauled out of the mine, dumped, and returned empty into the mine without ever becoming uncoupled from the cable.

My invention furthermore contemplates the construction, especially with new mine workings, of a tipple built on trestle work, together with screening, washing, and classifying means for the values beneath the head of the tipple whereby the values may be sorted and loaded for shipment.

2

The refuse, which from a coal mine would consist principally of slate, is dumped beneath the tipple and when the space is filled up, I contemplate the provision of cross conveyors for carrying the refuse laterally away from the tipple.

Apparatus embodying features of my invention is illustrated in the accompanying drawings, forming a part of this application, in which

Figs. 1 and 2 are plan views of a mine having my improved system installed therein;

Fig. 3 is a sectional view taken along the line III—III of Fig. 1 and drawn to a larger scale;

Fig. 4 is an elevational view showing the delivery end of the system;

Fig. 5 is a plan view of the cable drive means employed with my improved haulage system;

Fig. 6 is a sectional view taken along the lines VI—VI of Fig. 5;

Fig. 7 is an elevational view, partly in section, 20 of the car dump employed with my improved system;

Fig. 8 is a sectional view taken along the lines VIII—VIII of Fig. 7;

Fig. 9 is a fragmentary plan view of the drive sheave for the cable;

Fig. 10 is a sectional view taken along the lines X—X of Fig. 9;

Fig. 11 is a diagrammatic view showing the means for disengaging car grabs from cable in the mine;

Fig. 12 is a detail view showing the manner of mounting a grab on the end of a car; and

Fig. 13 is a sectional plan view taken at a right angle to Fig. 12.

Referring now to the drawings for a better understanding of my invention, I show diagrammatically in Figs. 1 and 2 a mine working embodying a slope or tunnel 10, emerging from beneath the ground at 11, and outside the slope or tunnel a tipple 12. At the lower end of the slope or tunnel 10, drifts 13 and 14 may branch off to portions of the mine being worked. It will be understood, of course, that the showing just described is merely illustrative of a mine working to which my improved hauling system may be applied and that it is adaptable for various other workings. Within the slope or tunnel 10 are parallel tracks 16 and 17 upon which mine cars 18 are adapted to run. The cars 18 are hauled out of, and returned into, the mines by means of an endless cable 19 which passes around a drive sheave 21 at the head of the tipple 12, and around an idler sheave 22 at the innermost end of the slope or tunnel 10. The drifts 13 and 14

50 may also be provided with parallel tracks and

with separate, endless cables 23 and 24, each separately driven as by means of a motor 26, and drive sheave 27, operatively connected to the motor 26, as by means of a drive belt 28.

The cars 18 are detachably connected to the cable 19 by means of a grab 29 which is pivotally mounted at 31 on one end of each of the cars and which includes an arm 32 extending laterally and terminating in an upwardly opening V shape bend or notch 33. The pivotal mounting 31 includes a sleeve 30 which serves as a bearing for the lower end of the grab 29. See Figs. 12 and 13. The sleeve 30 is also mounted to rotate in a vertical plane by means of a bolt 35 which secures it to the end of the car. The grab is held in an upright position by means of a spring pressed latch 35'. By this means, the grabs may be turned down and detached cars pushed into position for loading where there is a minimum of head room. The cable 19 rests in the V-shaped notch 33 by gravity, and the notch being offset from the pivotal mounting 31 by reason of the lateral arm 32, grips the cable 19 with a frictional grip varying with the resistance to the pull on the cable. At the lower end of the slope or tunnel 10, near the idler sheave 22, I provide a pulley 34, over which the cable 19 is adapted to run and which raises the cable out of the notch 33 and disengages it from each car 18 as it approaches the lower end of the tunnel whereupon the detached cars are again loaded and hooked onto the cable. See Fig. 11. If desired, pulleys such as 34, disposed to raise the cable 19 out of the notches 33, may be placed in the tunnel at various points where it is desired to disengage or uncouple the cars from the cable. For example, it is desirable that cars be disconnected from the cable in order that they may be run into the side workings represented by the drifts 13 and 14. Accordingly, a pulley 34 should be located at each point along the cable 19 where it may be desired to uncouple the cars.

As shown in Fig. 4, with new workings, the tipple 12 is constructed to extend out of the mine at a relatively steep angle and is constructed on trestle work 36 and 37 which is intended to be of a temporary nature to be filled in with refuse from the mines indicated by the irregular line. The outer or head end of the tipple 12 is supported by means of beams 38 and overhangs a hemispherically shaped washing, screening, and classifying structure 39. In this structure, the values unloaded from the cars 18, for example coal, is delivered first to sizing screens 40 where it is separated as to sizes and delivered to a washing floor 45. After being washed, screened, and classified, the coal is loaded in bins such as indicated at 41 and 42, and the refuse from the washers, into a bin 43 from which they may be loaded in railroad cars 44 on tracks 46 running beneath the structure 39.

At 47 and 48, I indicate rotary car dumps which will be described in detail later. It is contemplated, especially with a new mine working, that two such dumps shall be employed, the first being employed for dumping slate or other refuse beneath the tipple 12 to fill in around the trestle work and the second for the values, or coal. Later on, the dump 47 may be dispensed with and both the values and the refuse dumped by the rotary dump 48 and the refuse conveyed laterally away from the tipple.

Referring now to Figs. 5, 6 and 9, the drive sheave 21 is supported by a suitable structure, such as the reinforced concrete foundation 49

shown in Fig. 6. It comprises a gear 51 having secured to the underside thereof the sheave portion proper 52, in which the cable 19 runs. As shown particularly in Figs. 9 and 10, the sheave portion 52 is provided around its periphery with fingers 53 which are adapted to engage the grabs 29 to haul the cars around the head end of the tipple, beneath the drive sheave 21, where the tracks 16 and 17 join. As shown in Fig. 9, the fingers 53 are formed with relatively widely diverging angles 54, whereby the grabs 29 may retain their grips on the cable 19.

The drive sheave 21 is driven from a motor 56 supported by the structure 49, and having two sprocket wheels 57 and 58 mounted on the upper end of its shaft 59. The sprockets 57 and 58 drive chains 61 and 62, which mesh with sprockets 63 and 64, respectively. The sprockets 63 and 64 drive shafts 66 and 67, mounted in bearings 68 and 69, which in turn are supported by frame work 65 mounted on the foundation 49. The sheave 21 and gear 51 are supported by roller bearings 70 mounted as shown in the foundation 49. At the lower ends of the shafts 66 and 67 are pinions 71 and 72, which mesh with the gear teeth on the gear portion 51, to drive the sheave.

Except as otherwise specified herein, the car dumps 47 and 48 are constructed and operated in a manner similar to the car dump shown in my prior Patent No. 1,787,762 dated January 6, 1931. Reference is accordingly made to said patent for their details of construction and manner of operation.

In accordance with my present invention, the cars pass through the rotary dumps, being drawn by the cable 19, and the grabs 29 are so positioned on the ends of the cars that the V-shaped notch on each is eccentric to the center of rotation of the riding rings 73 of the rotary dump which aids in holding the cable in place in the grabs 29 while a car is being dumped. Preferably, the cars 18 are constructed as shown and described in my co-pending application Ser. No. 542,018, filed June 24, 1944, and have outwardly curved sides 74 and 76. In order to provide substantial support for the cars while they are in the rotary dump and are being turned to dump the contents thereof, I provide a plurality of roller bearings 77 and 78 which fit the outwardly curved sides 74 and 76 of the cars. The rollers 77 and 78 are supported by means of steel beams 79 and 81 extending longitudinally of the dump and secured to the riding rings 73. By this means, when a car enters the rotary dump, and is turned through an angle of 180° or less to dump the contents thereof, it is supported by the roller bearings 77 and 78 and does not have to stop its travel through the dump. It is contemplated that the cars 18 shall travel at a rate of from 100 to 150 feet per minute, which gives ample time for them to be dumped and righted while in one of the dumps 47 or 48.

The riding rings 73 are adapted to rotate in either direction to dump the contents of a car either into a chute 82, or into a chute 83 both located beneath and leading laterally from the dump. When dumping into the chute 83 the riding rings 73 rotate clockwise, as viewed in Fig. 8, and a vane 84, pivoted at 86, centrally beneath the dump is turned by means, not shown, to the full line position shown in Fig. 8 to cause all material to flow down the chute 83. When dumping into the chute 82, the riding rings rotate counter clockwise and the vane 84 is turned to its dotted line position shown in Fig. 8. Where coal and

refuse from the mine are being handled, for example, the coal may be directed down the chute 83 to the classifying and screening structure 39. If a car contains refuse or slate, the vane 84 is turned to the dotted position shown in Fig. 9 so that the refuse is dumped into the chute and be carried away laterally from the tipple by any suitable means, not shown.

From the foregoing it will be apparent that I have devised an improved mine haulage system by means of which the products of a mine may be economically removed and disposed of in a minimum of time and with a minimum of labor. It will furthermore be apparent that this improved system embodies an improved cable driving and car dumping mechanism which obviates the necessity of uncoupling the cars from the cable as they are brought out of the mine.

While I have shown my invention in but one form, it will be obvious to those skilled in the art that it is not so limited, but is susceptible of various changes and modifications, without departing from the spirit thereof, and I desire, therefore, that only such limitations shall be placed thereon as are specifically set forth in the appended claims.

What I claim is:

1. In a mine haulage system including an endless cable, and drive means for the cable, an upwardly inclined tipple, a rotary dump included in the tipple through which the endless cable passes, mine cars having outwardly curved sides,

V-shaped frictionally engaging grabs on the cars disposed to engage the cable, roller bearings mounted in the sides of the dump to engage the cars as they are hauled through the dump and of a length corresponding to the height of the sides of the cars and inwardly curved between their ends to fit against the sides of the cars and hold them as they are rotated.

2. In a rotary dump, a moving endless cable passing through the dump, mine cars having outwardly curved sides, grabs on the cars disposed to engage the cable to haul them through the dump, roller bearings mounted in the sides of the dump to engage the cars as they are hauled through the dump and of a length corresponding to the height of the sides of the cars and inwardly curved between their ends to fit against the sides of the cars and hold them as they are rotated, and means to rotate the dump as the cars are being hauled therethrough.

ERSKINE RAMSAY.
